US0D1085181S

(12) **United States Design Patent** (10) **Patent No.:** **US D1,085,181 S**
(45) **Date of Patent:** **** Jul. 22, 2025**

(54) **REFRIGERATOR**

(71) Applicant: **Samsung Electronics Co., Ltd.**, Suwon-si (KR)

(72) Inventors: **Hyeong-Ju Seo**, Suwon-si (KR); **Young-Min Park**, Suwon-si (KR); **Jae-Jun Kim**, Suwon-si (KR); **Seok-Woo Kim**, Suwon-si (KR); **Ae-Ryun Kim**, Suwon-si (KR)

(73) Assignee: **Samsung Electronics Co., Ltd.**, Suwon-si (KR)

(**) Term: **15 Years**

(21) Appl. No.: **29/807,966**

(22) Filed: **Sep. 16, 2021**

(30) **Foreign Application Priority Data**

Mar. 19, 2021 (KR) 30-2021-0013334

(51) **LOC (15) Cl.** **15-07**

(52) **U.S. Cl.** **D15/91**
USPC .....

(58) **Field of Classification Search**

USPC D15/79, 80, 81, 82, 83, 84, 85, 86, 87,
D15/88, 89, 91

CPC F25D 23/028; F25D 2323/024; F25D
25/025; F25D 23/067; F25D 2325/022

See application file for complete search history.

(57) **CLAIM**

The ornamental design for a refrigerator, as shown and described.

DESCRIPTION

FIG. 1 is a front perspective view of a refrigerator showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The evenly dashed broken lines in the figures depict portions of the refrigerator which form no part of the claimed design.

1 Claim, 7 Drawing Sheets
